(57) **CLAIM**

The ornamental design for a containment member for floor care apparatus, as shown and described.

DESCRIPTION

FIG. 1 is a front isometric view of a containment member for floor care apparatus showing our new design;

FIG. 2 is a front elevational view thereof;

FIG. 3 is a rear elevational view thereof;

FIG. 4 is a right side elevational view thereof; and,

FIG. 5 is a top plan view thereof.

Portions of the accompanying drawings that appear in phantom lines are provided to illustrate an environment of the invention and do not form part of the invention as claimed.

1 Claim, 3 Drawing Sheets
